UNITED STATES PATENT OFFICE.

DONALD R. FRUCHEY, OF NAPOLEON, OHIO.

LIGHT DIFFUSER FOR HEADLIGHTS.

Application filed November 4, 1927. Serial No. 230,967.

This invention relates to reflectors, but more particularly to head light reflectors for automobiles.

An object of this invention is to produce a reflector for automobile headlights which is capable of providing maximum light for the road, but eliminates the blinding glare to approaching vehicles.

A further object is to provide an auxiliary glare-eliminating reflector for automobile headlights. Other objects and advantages will hereinafter appear.

The invention is shown by way of illustration in the accompanying drawings, in which:

Fig. 1 is a front elevation of an automobile headlight with part of the lens broken away; Fig. 2 is a transverse sectional elevation of the lamp shown in Fig. 1; and Fig. 3 is a side elevation of the auxiliary reflector.

The illustrated embodiment of the invention comprises an automobile headlight 1 having the usual main reflector 2 and lens 3. Concentric of the concavo-convex reflector 2 is a socket member 4 to receive the lamp 5 having bayonet connection with the socket, as will be readily understood, leads 6 extending into position for contacting the lamp contact piece.

Concentric with the main reflector 2 is an auxiliary reflector 7 which is considerably smaller than the main reflector, and is shown as being held in place by the lamp 5, a central opening being formed in the reflector to receive the lamp. The reflector 7 is of concave form and may be formed of material similar to the main reflector 2 having an inside reflecting surface. The auxiliary reflector 4 is formed with pairs of horizontal slits which provide vertical segments 8 and opposed side segments 9, the segments of each pair being substantially equal. As most clearly shown in Fig. 3, the segments 8 overlap the segments 9, and the several segments are turned or inclined inwardly toward the axis thereof.

It will be understood that the light rays emanating from the lamp 5 are reflected by the auxiliary reflector 7 in such a manner that the glare to approaching vehicles is elimi-

nated, because the segments 8 direct the light rays respectively downwardly and upwardly as well as sidewardly, at such an angle as to avoid the line of vision of occupants in approaching vehicles. As shown in Fig. 3, the segments 8 are inclined inwardly approximately 30° from the vertical, and the side segments 9 are similarly inclined inwardly. The various segments are bent along lines spaced from the central aperture provided in the reflector 7 to receive the lamp, the lines of bend being in juxtaposition to the main reflector 7 so as to be capable of engaging the reflector 7 to hold the latter in position. It is to be understood that the light rays passing beyond the auxiliary reflector 7 and impinging on the main reflector 2 are reflected outwardly, but as will be apparent to those skilled in this art, the glare from vehicle headlights is caused by that region in close proximity to the lamp, so that the remainder of the main reflector utilizes its full reflecting surface away from the auxiliary reflector.

While I have shown and described the invention in connection with an auxiliary reflector having a definite number of segments, it is to be understood that the number and positioning of these segments may be varied as desired. Other changes and modifications in details of arrangement and construction may be effected without departing from the spirit of the invention as defined in the appended claim.

What I claim as new and desire to secure by Letters Patent is:

An auxiliary reflector for use with headlights having a main reflector and an electric lamp, composed of a body having a central opening to receive the lamp and having a plurality of aligned horizontal slits located above the opening and a plurality of aligned horizontal slits located below the opening to form elongated upper and lower segments and short intermediate segments, the outer end parts of the segments being bent forwardly along lines connecting the slits.

In testimony whereof I have hereunto signed my name to this specification.

DONALD R. FRUCHEY.
